DRIER DRUM

Earl E. Berry, Beloit, Wis., assignor to Beloit Iron Works, Beloit, Wis., a corporation of Wisconsin

Application July 31, 1939, Serial No. 287,507

7 Claims. (Cl. 34—9)

This invention relates to drier drum constructions, and more particularly to Yankee driers having highly polished bronze peripheral surfaces supported on ferrous metal trunnions which are initially stressed to compensate for differences in expansion of the non-ferrous metal and ferrous metal parts so that the stresses are relieved when the driers are heated to drying temperatures.

Drier drums for producing machine glazed paper webs should have perfect, smooth web-receiving surfaces free from scratches, pits and the like. These drier drums are made from cast metal cylinders, and many mechanical grinding and polishing operations are necessary to smooth off the web receiving surfaces of the castings. However, the usual cast metal cannot be polished sufficiently to produce a perfect, smooth surface, and cast ferrous metals in particular are pitted, scratched and irregular, even after the most thorough polishing operations.

Since in the Yankee type Fourdrinier paper machine the newly formed paper web is directly contacted with the Yankee drier, any irregularities in the drier surface will be reproduced on the web. Furthermore, any pits in the drier surface will form steam or vapor pockets tending to blow the sheet off the drum surface and hinder efficient drying. As a result, it has been heretofore necessary to dry at low temperatures so that the steam or vapor formation is sufficiently slow to permit its being bled through the sheet without developing appreciable pressures under the sheet.

This invention now provides a composite drier drum having a cast bronze cylinder mounted on a ferrous metal trunnion. The bronze alloy used in forming the cylinder is fine grained and dense, possesses ductility, hardness and strength, is an excellent heat transfer medium, and can be polished to provide a perfect mirror-like surface free from scratches, pits and the like.

According to the invention, the cast bronze cylinder is provided with bronze concave heads or end walls. A ferrous metal axle or trunnion extends axially through the cylinder and is force-fitted into the apertures of the bronze heads. The axle has head-receiving shoulders thereon spaced apart for a distance greater than the normal spacing between the aperture defining rims of the heads. The heads are then sprung outwardly into tight engagement with the axle shoulders so that the construction is stressed both axially and radially. When the composite drum is heated to drying temperatures, the bronze cylinder and heads expand more than the

ferrous metal axle and the stresses are relieved.

The use of ferrous metal such as iron or mild steel for the axle construction effects large savings since in the larger drier drums this supporting shaft may weight as much as twenty tons. In addition, the cast iron or mild steel possesses great strength.

It is then an object of the invention to provide drier drums for the production of superior machine glazed paper.

Another object of the invention is to provide drier drums having perfect mirror-like peripheral surfaces composed of cast non-ferrous metal.

Another object is to provide composite drier drum constructions including cast non-ferrous cylinders mounted on cast ferrous metal trunnions.

A further object of this invention is to provide a composite metal drier drum having an initial stress that is relieved when the drum is brought up to drying temperature.

A specific object of the invention is to provide a Yankee drier having a bronze cylinder and bronze heads mounted under stress on an iron or steel trunnion.

Other and further objects of the invention will become apparent to those skilled in the art from the following detailed description of the annexed sheets of drawings which disclose a preferred embodiment of the invention.

On the drawings:

Figure 1 is a vertical cross-sectional view, taken longitudinally through a drier drum according to the invention;

Figure 2 is a transverse cross-sectional view, taken along the line II—II of Figure 1;

Figure 3 is an enlarged fragmentary vertical cross-sectional view illustrating the manner in which the drum is initially stressed on its supporting trunnion;

Figure 4 is a greatly enlarged cross-sectional view of a web of paper being dried on a drum according to this invention;

Figure 5 is a fragmentary plan view of the web shown in Figure 4 and illustrating the machine glazed drum contacting surface of the web;

Figure 6 is a greatly enlarged vertical cross-sectional view of a web of paper being dried on the usual drum drier;

Figure 7 is a plan view of the web dried on the drum shown in Figure 6 and illustrating the pock-marked machine glazed drum contacting surface of the web; and

Figure 8 is a greatly enlarged vertical cross-sectional view taken through the usual periphery

of a drum drier and illustrating the effect of a pit in the drum surface on the web being dried on the surface.

As shown on the drawings:

As best shown in Figure 1, the reference numeral 10 designates generally a drier drum composed of a cast bronze hollow cylinder 11 bolted to concave or dished cast bronze heads 12 by means of bolts 13. The heads 12 form end walls for the cylinder 11.

Both heads 12 are centrally apertured as at 14 to receive a cast iron or cast mild steel axle or trunnion designated generally by the reference numeral 15.

One of the heads 12 can have a second aperture 16 therein to provide a manhole giving access to the interior of the drum 10. The aperture 16 can be closed with a plate or cover 17.

The axle or trunnion 15 is composed of two hollow axially aligned parts 18 and 19 having a separator plate 20 therebetween. The plate 20 is provided with a thickened rim portion 21 abutting flanges 22 extending outwardly from the inner ends of the parts 18 and 19. Bolts 23 extend through the flanges 22 and thickened rim 21 of the plate 20 for securing the parts together. The thickened rim 21 is radially drilled at intervals therearound on the side of the plate facing the axle part 19, as indicated at 24. Steam nozzles 25 are threaded into the holes 24 for distributing steam from the interior of the axle part 19 into the interior of the drum.

The axle part 18 has diametrically opposed transverse apertures 26 therethrough. Flanges 26a are cast integrally on the axle part 18 around the apertures 26 to reinforce the construction.

Each of the axle parts 18 and 19 have enlarged annular head portions or collars 27 formed with circular rims 27a which are press fitted into the apertures 14 of the heads 12. Shoulders 27b project radially from the rims 27a and form back walls for these rims. The shoulders 27b are spaced apart at a greater distance than the normal distance between the aperture defining rims of the heads 12, as best shown in Figure 3. Bolts 28 extend through the heads 12 and through the shoulders 27b to draw the heads outwardly against the shoulders 27b, as shown in dotted lines in Figure 3. This springs the concave heads 12 outwardly and places the assembly under axial stress. As also best shown in Figure 3, the rims 27a are press-fitted into the apertures 14 of the heads 12 so that the fit between the rims and the heads produces a radially stressed assembly.

However, since the bronze cylinder 11 and the bronze heads 12 have a greater coefficient of thermal expansion than the iron or steel axle 15, they will expand at a faster rate than the axle when the drier drum is heated to drying temperature. Hence, the cylinder will elongate axially more than the axle will elongate axially, and the heads will be carried outwardly. This expansion of the cylinder 11 will relieve the axial stress caused by the initial outward springing of the heads. Furthermore, the heads themselves will expand radially at a rate greater than the rim portions 27a of the axle. The initial, radially stressed press fit between the rims and the bronze heads will thus be relieved. Under the circumstances, the assembly is unstressed at its operating temperature.

The axle part 18 has a hollow trunnion portion 29 projecting outwardly from the collar 27. This trunnion 29 is adapted to be mounted in a bear-

ing for rotatably supporting the drum. A condensate removal pipe 30 is mounted in the trunnion 29 and abuts a seal 31 at its inner end.

A pipe 32 is mounted in the axle part 18 and receives a T fitting 33 at its inner end. The outer end of the pipe 32 communicates with the pipe 30 at the seal 31. Drain pipes 34 and 35 extend from the fitting 33 through the apertures 26 of the axle part 18 and can be clamped to the thickened rim 26a by means of clamps 36. The pipe 34 extends through the top aperture 26 and is curved downwardly to the bottom of the cylinder 11, as best shown in Figure 2. The pipe 35 extends through the bottom aperture 26 of the axle part and is curved upwardly to the top portion of the cylinder 11.

Condensate dippers or scoops 37 are mounted on the ends of the pipes 34 and 35 adjacent to the cylinder 11 and serve to scoop up steam condensate from the interior of the cylinder into the pipes. This condensate is then discharged out of the cylinder through the drain line 30. Additional brackets 38 can be bolted on the flanges 26a to rigidify the pipe lines 34 and 35 extending on the outsides of the axle part 18. This curved pipe construction permits expansion of the pipe lines when the cylinder is heated without unduly stressing the pipes.

The axle part 19 also has a hollow trunnion 39 extending outwardly from its head or collar 27. This trunnion 39 receives a steam inlet pipe 40 for supplying steam to the interior of the axle part 19. The steam will be ejected from the axle part 19 through the steam nozzles 25 to heat the cylinder 11. The condensate from the steam is removed from the cylinder as described above.

Therefore, according to this invention, the axle construction performs a quadruple function of rotatably supporting the drum; of initially stressing the assembly; of distributing steam to the interior of the drum, and of removing steam condensate from the drum.

As shown in Figure 4, the bronze cylinder 11 of the drier drum 10 has a smooth polished, continuous, flat surface 41 receiving the web W thereon. The cylinder 11 is preferably a cast bronze alloy known commercially as "D H S Bronze." This bronze alloy has extremely fine and dense grain structure, has high heat transfer properties, and can be polished to a mirror-like degree. Due to the fineness and density of the grain structure, no pits are formed during the polishing operation.

The preferred bronze alloys for forming the cast cylinder 11 have the following physical properties:

Ultimate tensile strength.—90,000 to 120,000 pounds per square inch.

Yield point.—45,000 to 95,000 pounds per square inch.

Elastic limits.—40,000 to 60,000 pounds per square inch.

Elongation.—25 to 10% in two inches.

Reduction of area.—25% to 10%.

Brinell hardness.—185 to 250.

A specific alloy within the above range that is satisfactory has the following physical properties:

Ultimate tensile strength.—119,400 pounds per square inch.

Yield point.—94,200 pounds per square inch.

Elongation.—15% in two inches.

Reduction of area.—15.5%.

Brinell hardness.—235.

The smooth continuous surface 41 of the cylinder 11 is imparted to the cylinder contacting surface 41a of the web W to produce a perfect machine glazed finish on the web.

As shown in Figure 6, the usual cast metal cylinder 11a has a rough surface 42 full of pits 43 which cannot be polished out of the metal. This rough surface 42 will form a correspondingly rough surface 42a on the paper web W' being dried thereon. The surface 42a is full of pock marks 43a from the pits 43. As a result the machine glazed web W' is highly imperfect.

As shown in Figure 8, the pits 43 in the surface of the usual drum cylinder 11a will form a steam pocket 44 under the web W' since the steam generated from the water in the web W' becomes entrapped between the web and the cylinder. This trapped steam will actually blow the web W' off of the surface of the cylinder with a result that the web is not uniformly dried.

In order to minimize the blowing of the webs off of driers it has heretofore been necessary to operate at lower drying temperatures than are now possible. As a result, the heretofore known driers have been slow. This invention, by providing a smooth continuous drying surface makes possible a thorough contact between the web and the heated drying surface. As a result, higher drying temperatures can be used and the drying operation is speeded up considerably.

From the above description it should be understood that this invention makes possible the production of perfect machine glazed paper webs at speeds that were heretofore unobtainable.

It will, of course, be understood that numerous details of construction may be varied through a wide range without departing from the principles of this invention, and it is therefore not the purpose to limit the patent granted hereon otherwise than necessitated by the scope of the appended claims.

I claim as my invention:

1. A Yankee drier comprising a cast bronze cylinder for receiving a wet web of paper thereon, said cylinder having a highly polished mirror-like continuous peripheral surface free from pits and irregularities and composed of a fine grained, dense bronze alloy with an ultimate tensile strength of from 90,000 to 120,000 pounds per square inch, a yield point of from 45,000 to 95,000 pounds per square inch, an elastic limit of from 40,000 to 60,000 pounds per square inch, and a Brinell hardness of from 185 to 250 whereby said surface can be highly heated to rapidly dry a wet web of paper thereon without formation of vapor pockets under the web.

2. A drier drum assembly comprising a bronze cylinder having a polished continuous peripheral surface, a ferrous metal axle extending through said cylinder to rotatably support the cylinder, means connecting the cylinder and axle to stress the same in opposite axial directions when cold, and means for heating the cylinder to axially expand the same at a higher rate than the axle for relieving the stress.

3. A drier drum construction comprising a hollow metal cylinder, stiff springable concave heads secured to the ends of said cylinder, said heads having central apertures therethrough, a hollow metal trunnion extending through said cylinder and said apertures in said heads, said trunnion having rim portions force-fitted into said apertures, said rim portions having back walls spaced outwardly from said heads when the heads are unsprung, and bolts drawing said heads against said back walls to spring the heads outwardly whereby said drum construction is stressed radially and axially.

4. A drier drum assembly adapted for the production of machine glazed paper which comprises a hollow metal cylinder, stiff springable concave heads closing the ends of said cylinder, a hollow metal trunnion having a lower coefficient of expansion than said cylinder and said heads extending through the cylinder and force-fitted in the heads, means springing said heads outwardly into fixed connection with said trunnion whereby said assembly is under radial and axial stresses, means for introducing a heating fluid to said drum to relieve said stresses and heat the cylinder, and means for removing spent heating fluid from the drum.

5. A drier drum comprising a cast bronze hollow cylinder having a highly polished peripheral surface, concave cast bronze heads secured to the ends of said cylinder and having central apertures therethrough, a hollow ferrous metal trunnion extending through said cylinder and having enlarged rim portions force-fitted in said apertures, shoulders adjacent said rim portions, bolts springing said heads outwardly against said shoulders, a dividing wall in said trunnion, steam jets on one side of said dividing wall communicating with the interior of the trunnion and the cylinder, means for introducing the steam to said steam jets, steam condensate drain lines extending into said cylinder from said trunnion on the opposite side of the dividing wall whereby radial and axial stresses are relieved when steam is introduced into the drum to heat the cylinder due to the higher rate of expansion of said bronze material members over said ferrous metal trunnion.

6. The method of making machine glazed paper which comprises contacting wet paper with the highly polished bronze surface of a heated, fine grained bronze drum, and vaporizing the moisture in said paper at a rapid rate without blowing the paper off said surface.

7. The method of rapidly drying wet paper webs to impart a machine glazed finish thereon which comprises intimately contacting a wet paper web with the mirror-like continuous surface of a rotating drum composed throughout its cross-sectional depth of cast fine-grained dense bronze, and continually heating said surface to a high temperature to rapidly drive moisture from the web, whereby the continuity of the surface will eliminate vapor pockets between the web and the surface.

EARL E. BERRY.
